CHARLES J. DAHLGREN, OF EAST ORANGE, NEW JERSEY.

BUCKLE.

Application filed August 13, 1926. Serial No. 128,932.

This invention relates to buckles and particularly to that type in which the free end of the strap or belt may be passed underneath both ends of the buckle frame and over the fastening member of the buckle for concealing the fastening or gripping member and exposing the frame only to view.

My invention contemplates the provision of a simple frame and fastening member each adapted for economical manufacture in large quantities from sheet material. The fastening member is designed to be pivoted to the frame in such a way that movement of said member causes no movement of the strap or belt end which is permanently attached thereto. Simple and efficient cooperating gripping elements are provided on the frame and on the fastening member for quickly and effectively securing the adjustable or free end of the strap or belt in the buckle without danger of displacement, and without puncturing the material of the belt.

The various objects of my invention will be clear from the description which follows and from the drawings, in which

Fig. 1 is a front elevation of my improved buckle.

Fig. 2 is a side view of the same.

Fig. 3 is a cross section of the same, showing a belt arranged in its secured position in the buckle.

Fig. 4 is a perspective view of the same, and

Fig. 5 is a front elevation of a blank from which the frame of my improved buckle may be made.

In the illustrated application of my invention, showing one of the practical embodiments thereof, a blank as 10 is provided with a comparatively large and substantially central opening 11 therein and with preferably circular side apertures as 12. One end 13 of the blank is made preferably about twice as wide as the other end 14 thereof, the sides 15 and 16 of the blank being made substantially alike. To form the finished frame, the sides 15 and 16 are bent at substantially right angles to the face of the blank about the dotted lines 17 of Fig. 5 whereby the edges 18 and 19 of the respective sides are arranged in the opening 11. When the buckle is secured to a belt in its adjusted position, said edges 18 and 19 join the ends 14 and 24 to give a pleasing rec-

tangular outline to the face of the buckle 55 frame, which is then the only part visible.

The blank end 13 is bent into substantially U-form in cross section about a line nearer the inner edge 21 of the opening 11 than the extreme edge 22 of said end, whereby the 60 upper arm or end 24 forms the frame end, and the lower arm 23 forms a ledge wider than and underneath the frame end 24. The inner edge 22 of the ledge 23 inwardly underhangs or projects beyond the edge 21 to a considerable extent, a space being provided between said frame end 24 and said ledge 65 for receiving a portion of the belt to be gripped, as will be more fully explained hereinafter.

The swingable member 25 is preferably flat and of the same thickness throughout so that it may be readily stamped of sheet material. Said member 25 is divided by the preferably rectangular slot 28 into a hinge bar as 26 and a belt-engaging bar as 27. The hinge bar 26 is somewhat narrower than the belt-engaging bar 27 and forms one end of the slot 28, the other end of said slot being formed by the bar 27. To provide means for pivoting the member 25 to the frame, side extensions as 29, preferably rectangular in outline and in alignment with the hinge bar 26, extend from the sides of said hinge bar and pass through the openings 12 in the frame sides 15 and 16. It will be noted that by pivoting the member 25 at the sides of the hinge bar, said bar may readily be utilized for securing the end of a belt thereabout without danger of moving 85 the secured end of the belt when the member 25 is manipulated. For making the connecting portions 30 or sides of the member 25 between the belt-engaging bar and the hinge bar as narrow as possible without weakening said connecting portions, the slot 28 is made as long as possible. It therefore becomes possible to secure the belt end 33 to the hinge bar without mutilation of said belt end, and to use a belt or strap 35 of substantially the full width of the inside of the frame.

Along that end 34 of the member 25 furthest from the hinge bar, I prefer to make a series of shallow, curved, intersecting indentations as 31, whereby a series of obtuse points 32 are formed along said end. The member 25 is adapted to swing about the

pivotal extensions 29, and is made of sufficient length so that the points 32 just clear, or if preferred, just touch or reach the inner edge 21 of the frame end 24 during the 5 rotative movement of said member. For preventing too easy swinging of said member and for aiding in the maintenance of said member in the belt locking position, the width thereof from side to side is made preferably exactly the same as, or slightly greater than that of the opening 11, whereby the side edges of the connecting portions 30 engage the inside faces of the frame sides 15 and 16 and offer slight resistance to the final 10 closing or belt securing movement of said member.

I prefer to arrange the hinge bar 26 at one side of, but near the center line of the buckle frame, whereby a space as 36, sufficiently large to allow both the secured end 33 and the free end 37 of the belt 35 to pass therethrough and under the frame end 14. Similarly, the slot 28 is made large enough to allow the belt end 33 to pass completely 20 therethrough without mutilation and about the hinge bar 26, suitable stitching or other well known fastening means being used to form a secured loop 38 in the belt at said hinge bar.

30 To secure the free end 37 of the belt in adjusted position in the buckle, it is first passed under the ledge 23 and then past the points 32. The pivoted member 25 is then pressed towards the ledge, whereupon the 35 points 32 grip the material of the belt without going through or puncturing the belt and force the gripped portion into the space 39 between the frame end 24 and the ledge 23, as shown in Figs. 3 and 4. Since the 40 points 32 pass very close to the inner edge 21 of the frame end 24, said points will be forced slightly into the belt, but cannot pierce through because of their dullness or obtuse angle. The side portions 30 may at 45 the same time engage the sides 15 and 16 whereby the movement of the member 25 in either direction is slightly resisted. Tension on either end 33 or 37 of the belt cannot loosen the belt, but instead causes the 50 belt to be held more firmly. The belt is not injured by the dull points 32 through the frictional gripping action, which is nevertheless effective due to the double bend 40 formed in the belt. To loosen the belt, 55 the member 25 need only be pressed in a direction away from the ledge 23, whereby the pressure on the bend 40 is released without affecting the secured end 33 in any way, since said end is secured on the hinge bar 60 about which the member 25 is pivoted.

By making the frame end 24 of the same width throughout, I am able to utilize the full inside width of the buckle frame, so that a belt of the same width may be used therewith, whereby the pivoted member may

be completely concealed by the free end of the belt, leaving only the frame itself visible in the adjusted position of the belt, as will be clear from Fig. 4.

It will be seen that I have provided a 70 buckle designed to be easily and economically made of sheet material, that by mounting the pivoted member for movement about the bar to which the secured end of the belt is attached, I attain important advantages 75 as hereinbefore pointed out, and that various changes more or less obvious, and not necessary to be here set forth in detail may be made in the structure shown and described without departing from the spirit 80 and scope of this invention and the range of equivalents afforded by the appended claims.

I claim:

1. A buckle comprising a closed rectangular frame formed of a single piece of sheet material, depending apertured sides on said frame, a flat swingable member of the same thickness throughout, formed of a single piece of sheet material and divided by a substantially rectangular opening therein into a long flat narrow hinge bar at one side of said opening and a wider belt engaging bar on the other side of said opening and having an outer edge adapted to engage a belt, and side extensions on said hinge bar 95 passing through the apertures of said frame sides for pivoting said hinge bar to said frame in spaced relation to the end of said frame whereby said belt engaging bar is arranged almost in contact with the other end of said frame, and an unmitigated belt end may be passed under one end of the frame and over and about said hinge bar.

2. A buckle comprising a closed frame 100 formed of a single piece of sheet material, an end on said frame substantially U-shaped in cross section, including an upper arm of the same width throughout and having a straight continuous inner edge, a lower ledge projecting inwardly of the frame past 105 the upper arm, a flat member of a single piece of sheet material pivoted to said frame between the ends of the frame, slightly projecting points at one end of said member of such length as just to reach the inner edge 110 of said upper arm on the movement of said member for squeezing a portion of a belt passed between said points and the inner edge of said upper arm therebetween, and apertured sides on said frame bent at substantially right angles to the face of said frame for receiving said pivoted member, the upper edges of said sides and the upper 115 faces of the ends of the frame all lying substantially in the same plane.

3. A buckle comprising a frame, depending sides on said frame, and a swingable member formed of a single piece of sheet material having an opening therein and including a hinge bar integral with and form-

ing one end of said member on one side of said opening, lugs on said hinge bar inserted for swinging movement in the sides of the frame, and a belt engaging member on the other side of said opening.

4. A buckle comprising a frame, ends on said frame having continuous, straight and parallel inner edges, a hinge bar adjacent to one end of the frame and extending across the inside of said frame from one side of said frame to the other and parallel to said end, integral extensions on said hinge bar aligning therewith and journaled in the sides of said frame, a clamping bar having belt engaging points projecting therefrom and cooperating with said frame for gripping the underside of a belt only and for forming a fold in said belt, and narrow spaced parallel sides connecting said clamping bar and said hinge bar and providing a space therebetween, said hinge bar, clamping bar points, extensions and sides being all formed of a single piece of material.

5. A buckle comprising a closed frame having all points in one of the faces thereof lying substantially in the same plane, a substantially centrally slotted rectangular member, dull obtuse points formed by shallow curved indentations in, and projecting from one of the long ends of said member, short extensions projecting beyond and substantially at right angles to the sides of said member and in alignment with the other end of said member, pivoted to said frame between the ends thereof and a hinge bar adapted to receive an unmutilated end of a belt thereabout forming the other end of said member, extending between said extensions.

40 6. A buckle comprising a closed, centrally apertured frame having a substantially plane outer face, and a one-piece member having a slot therein and swingable entirely within the aperture of said frame for engaging both ends of a belt, comprising a belt gripping portion at one end of said member having an outer edge arranged in close proximity to, and to cooperate with, the frame end adjacent thereto for adjustably locking a belt in said frame between said outer edge and the inner edge of said frame end, a hinge bar at the other end of said member spaced inwardly from the other end of the frame and adapted to have the end of a belt secured thereabout, and means at the side extremities of and integral with said bar passing through the sides of said frame for pivoting said member to said frame whereby movement of said member causes no movement of the belt end secured to said bar, relatively to said frame, and whereby said member is completely concealed by the free end of the belt and the outer face of said frame is exposed to view.

65 7. A buckle comprising a one-piece frame

of thin sheet material and a one-piece belt-engaging member of thin sheet material having a long, wide slot therein and flat on both faces thereof comprising a hinge bar formed at one extreme end of said member, adapted to have a belt of substantially the inside width of the frame secured thereto, lugs integral with, and projecting from the ends of the hinge bar and inserted into said frame for rotative movement therein, and a belt 70 engaging bar at the other end of said member in spaced relation to and lying in the plane of said hinge bar and a belt engaging edge on said belt engaging bar arranged to just clear all of the inner edge of said frame 75 on the rotation of said member, whereby the belt end to be secured to said hinge bar may be passed through the slot in said member between said bars and whereby said member is completely concealed by the free 80 end of the belt and the outer face of the frame is exposed to view, said hinge bar, slot, and belt engaging bar, all being arranged on the same side of said lugs.

8. A buckle comprising a flat closed frame, 90 a thin flat member of a single piece of thin sheet material for engaging the free end of a belt and for having the other end of the belt passed thereabout and secured thereto comprising a series of obtuse-angled, shallow 95 points projecting slightly from one end thereof, narrow sides substantially perpendicular to and integral with said pointed end, a hinge bar at the ends of said sides, in spaced relation to and substantially parallel to said pointed end and about which an unmutilated end of a belt may be secured, and flat extensions on said hinge bar passing through and pivoted in the sides of said 100 frame between the ends of said frame whereby said member is arranged for movement in said frame about said extensions as a pivot, and the secured end of the belt remains stationary on the movement of said member, and whereby said member is concealed by the free end of the belt and the 105 entire outer face of the frame is exposed.

9. A buckle comprising a substantially rectangular closed frame of single piece of thin sheet metal having a substantially rectangular opening therein and having all points on the outer face thereof lying on the same plane, and a member pivoted in the sides of said frame, said member being composed of a single flat piece of sheet metal including a belt-engaging bar of greater width than that of the ends of said frame, dull, obtuse angled, shallow points projecting from said bar up to the inner edge of the adjacent end of said frame, narrow sides 115 on said member integral with and substantially perpendicular to said bar, and a hinge bar parallel to and in spaced relation to said belt-engaging bar, integral with said sides 120 and adapted to have a belt end secured there- 125

130

4
to, and extensions on said hinge bar projecting beyond said sides and journaled in the sides of said frame between the ends of said frame, whereby movement of said member causes no movement of the belt end secured thereto, all of the points of the outer face of said member lying in a single plane parallel to the plane of the outer face of said frame when said member is in its belt-engaging position.

10. A buckle comprising a closed frame having an opening therein and having all points of the outer face thereof lying in the same plane, a ledge at one end of, bent out of the plane of, and substantially parallel to the outer face of, said frame, a straight inner edge on said frame forming one of the ends of the frame opening, a terminal edge on said ledge projecting inwardly past and in spaced relation to said inner edge, a swingable member, a hinge bar adapted to have a belt end secured thereto forming one end of said member pivoted in and between the ends of said frame, and means at the other end of said member cooperating with said inner edge and said ledge for adjustably gripping the free end of a belt.

11. A buckle comprising a closed rectan-

30 gular buckle frame formed of a blank of sheet material having a substantially rectangular opening therein, depending sides on said frame arranged with the thin edges thereof substantially in the plane of the face of the frame and having a pair of side openings therein, a bent end on said frame comprising a flat upper frame end of substantially the same width throughout the entire length thereof as the other end of said frame, arranged with the face thereof substantially 35 in the plane of the edges of said sides and substantially perpendicular to the wide surfaces of said sides and having a straight continuous inner edge lying in the plane of the face of said frame, and a flat lower ledge bent from, substantially parallel to, and extending inwardly past the inner edge of, said upper frame end, and a second flat end on said frame parallel to said first mentioned end and arranged in the plane of the face of said frame, and swingable means pivoted 40 to said frame at the side openings of said depending sides and adapted to cooperate with said inner edge of the frame and the ledge for removably engaging a belt.

45 50 CHARLES J. DAHLGREN.
